UNITED STATES PATENT OFFICE.

HENNING BERG AND CHARLES L. JANSEN, OF CHICAGO, ILLINOIS.

AUTOMATIC CHECK-VALVE FOR SEWERS.

1,182,524.

Specification of Letters Patent.

Patented May 9, 1916.

Application filed February 10, 1916. Serial No. 77,377.

To all whom it may concern:

Be it known that we, HENNING BERG and CHARLES L. JANSEN, citizens of the United States, and residents of Chicago, in the county of Cook and State of Illinois, have invented certain new and useful Improvements in Automatic Check-Valves for Sewers, of which the following is a specification.

This invention relates to certain new and useful improvements in an automatic check valve for sewers or drain pipes, and it consists in certain peculiarities of the construction, novel arrangement and operation of the various parts thereof as will be herein-after more fully set forth and specifically claimed.

The principal object of the invention is to provide a valve of the above mentioned type, which shall be simple and inexpensive in construction, strong, durable and efficient in operation, with its parts so made that the device can be readily installed within the drain pipe or removed therefrom to permit inspection, cleaning, or repair.

Another object is to so construct and arrange the parts of the valve, that it will automatically close the opening of the drain pipe so as to prevent the escape of sewer-gas, as well as the back flow of water from the sewer into the basement or other place where the drain may be located, should the sewer become clogged or flooded.

Other objects and advantages of the invention will be disclosed in the subjoined description and explanation.

In the accompanying drawing which serves to illustrate an embodiment of our invention—Figure 1 is a plan view thereof and Fig. 2 is a vertical sectional view taken on line 2—2 of Fig. 1 looking in the direction indicated by the arrows, showing the parts in their normal positions.

Corresponding numerals of reference refer to like parts throughout the views of the drawing.

While our invention is more particularly intended for use in the drain pipes which lead from the basement to the sewer, and while, in the present instance we have shown said pipe with its upper end located in the cement or concrete floor of a basement, yet it will be understood that our automatic check valve is adapted for use in drain pipes of various sizes, whether they are located in basements or other places, and for this reason we do not wish to be understood as

limiting ourselves in the use of the valve to any particular kind of drain pipe.

In the drawing, the reference numeral 3 designates a section of the cement floor of the basement, or a portion of the ground in which the drain pipe 4 is located, which pipe leads from near the upper surface of the floor or ground 3 to a sewer or sewer pipe, not shown, in the usual way. As shown in Fig. 2 of the drawing, the upper end of the pipe 4 is located within an opening 5 in the ground or floor 3 so that its upper end will be situated at a slight distance from the upper surface of the floor or ground. Located on the upper end of the pipe 4 is an anchor ring 6 which is embedded in the cement 3 and by preference has its upper inner edge provided with a groove 7 in which can be located suitable packing 8 of any desired kind, to form a close joint between the annular flange 9 on the upper end of a circular shell or casing 10 which may be made of any suitable size and material, but preferably of cast iron and tapered toward its lower end 80 as is clearly shown in Fig. 2 of the drawing. The lower end of the shell or casing 10 is formed with a valve seat 11 to receive the upper portion of a float valve 12 which is hollow, and by preference made of copper. 85 The flange 9 of the shell 10 is provided at points diametrically opposite each other on its inner portion with recesses 13 to receive the ends of a cross bar 14 which is provided centrally with a depending lug or boss 15 90 to which the upper end of a tubular member 16 is secured by means of a rod or pin 17 which is extended through suitable openings in the tube 16 and boss 15 as will be readily understood. Located in the lower portion of the tubular member 16 is a disk 18 which is held in place by means of in-turned flanges 19 on the lower end of said member. The disk 18 is provided centrally with an opening through which is extended 100 a rod 20 which projects into the tubular member 16 and has on its upper end a nut 21 of any suitable material. Interposed between the head 21 and the disk 18 is a coiled spring 22, the tension of which is sufficient to normally hold the float valve 12 in its seated position as shown in Fig. 2, but so that when a small quantity of water enters the casing 10 said spring will yield so as to allow the water to escape between the 110 valve seat 11 and the upper portion of the float valve. The rod 20 is extended cen-

trally through the float valve 12 and fastened to the bottom of the latter. The movement of the rod 20 through the opening in the disk 18 is free, and said disk is used 5 as a guide for said rod so as to cause the float valve 12 to seat properly.

Located on the upper surface of the flange 9 of the casing 10 is a grated cover 23 of the ordinary or usual construction which 10 can be secured to the said flange by means of screws 24 extended through suitable openings in the cover 23 to engage like openings in the flange 9 of the casing or shell 10. The openings 25 in the cover 23 15 will permit water to pass through said opening, yet will catch straw or litter, or in other words, said cover will act somewhat like a strainer.

It will be observed that the outer edges of 20 the cover 23, the flange 9 and the outer surface of the shell or casing 10 are downwardly tapered so that they may be easily withdrawn by removing the screws 24 or readily and accurately placed in position. The float 25 valve 12, tubular member 16 and spring 22 are by preference made of material which will not readily corrode or rust.

From the foregoing and by reference to the drawing it will be readily understood 30 and clearly seen that by constructing a check valve according to our improvements, the valve 12 will always be maintained by the action of the spring 22 in a closed position so as to prevent the escape of gases from 35 the sewer into the basement, yet whenever water accumulates on the floor or ground 40 it will pass through the openings 25 of the cover into the shell or casing 10 and onto the upper portion of the valve 12, when by 45 reason of the weight of the water within the casing, said valve will be depressed and permit the water to pass from the shell or casing 10, out through the drain pipe. In the event of back flow of water by reason of 50 the stoppage or flooding of the sewer, it is apparent that the float valve 12 will be

raised and seated thus preventing the escape of water through the shell 10 into the basement.

Having thus fully described our invention, 50 what we claim as new and desire to secure by Letters Patent is—

1. In an automatic check valve for sewers and the like, the combination with a drain-pipe, of a downwardly tapered casing 55 located therein and having a valve seat in its lower end and an annular flange at its upper end to provide a support therefor, a bar extended diametrically across the upper end of said casing, a tubular member mounted on the lower surface of said bar, a spring-actuated rod extended into said member from the lower end thereof, and a float-valve mounted on the lower portion of said rod and adapted to close the seat therefor 60 of the said casing.

2. In an automatic check valve for sewers and the like, the combination with a drain pipe, of an anchor ring mounted on the upper end thereof and having a groove in its 70 upper inner portion, packing in said groove, a downwardly tapered casing located in said ring and pipe and having a valve seat in its lower end and an annular flange at its upper end to rest on said ring, a bar extended 75 diametrically across said flange and seated at its ends therein, a projection on the central lower portion of the bar, a tubular member fastened to said projection, an apertured disk in the lower end of said member, a rod extended through said aperture into said member and having a head on its upper end, a spring interposed between said head and disk, and a float valve mounted on the lower portion of said rod to close the 80 seat therefor in the said casing.

HENNING BERG.
CHARLES L. JANSEN.
